UNITED STATES PATENT OFFICE

EDWIN L. BADGER, OF SPOKANE, WASHINGTON, ASSIGNOR TO DOHERTY RESEARCH COMPANY, OF NEW YORK, N. Y., A CORPORATION OF DELAWARE

WATER HEATER

Application filed September 15, 1928, Serial No. 135,558. Renewed May 31, 1928.

My present invention relates to improvements in water heaters of the type employing liquid or gaseous heaters, and utilized in connection with the well known stand boiler for 5 domestic purposes.

The invention involves the use of an upright casing or stand pipe in which is contained the heating elements in the form of a flue and means are provided in the flue for 10 causing a return draft of the heating gases. As thus constructed, the heating element is provided with a maximum heating surface and the water casing or hot water tank associated therewith is arranged to distribute 15 the water over the heating surface in a comparatively thin jacket in order that a large quantity of water may be heated in a minimum period of time.

The invention consists in certain novel 20 combinations and arrangements of parts for accomplishing the above results and objects, as will hereinafter be more fully pointed out and claimed.

In the accompanying drawings I have illustrated one complete example of the physical embodiment of my invention wherein the parts are combined and arranged according to one mode I have thus far devised for the practical application of the principles of my 30 invention.

Figure 1 is a view showing in elevation the well known type of stand boiler, and in vertical section the water heater connected therewith and involving the improvements 35 of my invention.

Figure 2 is a transverse sectional view at line 2—2 of Figure 1.

Figure 3 is a transverse sectional view at line 3—3 of Figure 1.

40 In order that the utility and general arrangement and relation of parts of the invention may readily be understood I have indicated in Figure 1 a stand boiler 1 having the cold water inlet pipe 2 leading into the top thereof as usual; a cold water faucet 3 and pipe-connection 4 at the bottom of the stand boiler, and the usual coupling nut 5. At the top of the stand boiler the hot water pipe 6 is provided with a similar coupling nut 7, 45 and connection is made to the water-heater

casing 8 by the cold water pipe 9 from coupling 5 and the hot water pipe 10 to the coupling 7, to provide for the required circulation of water through the heater and stand boiler.

The hot water casing or tank 8 is preferably of cylindrical construction with a comparatively small diameter with relation to its height, which as shown is greater than the height of the stand boiler, and the tank, shown as provided with a closed top is closed at its bottom by means of a screw cap 11. Within the tank is located the cylindrical flue 12 concentric with the walls of the tank and forming within the latter an annular, hot water space, or water jacket in contact with the walls of the flue. The space is comparatively narrow in order that the water, as a thin film or jacket, may receive or absorb heat throughout an extensive area, from the enclosed flue, thus insuring a large quantity of hot water in a short time, and increasing the effectiveness of the circulation of water between the hot water tank and the stand boiler.

To secure the flue within the tank the former is fashioned with an exterior flange 13 at its lower end and the screw cap 11 is utilized to fasten and retain the flue in position by engagement with this flange. The interior of the flue is divided by a vertically extending, central partition 14 extending from the bottom of the flue and terminating a short distance below the top closed end of the flue. In this manner an up-draft 50 passage and a down-draft passage are provided for the hot gases, and pairs of baffle plates 15 are fashioned rigid or integral with the partition for directing the gases into close contact with the inner surface of the walls of the flue to increase the heating effect. These baffle walls as best seen in Figure 2 are semi-circular in shape in order to provide narrow openings between their edges and the adjacent wall of the flue, and as the hot gases pass through these restrictions they are caused to impinge against the wall of the flue. To more directly cause this contact of the hot gases with the flue walls, the baffle plates are inclined slightly as 55

shown in Figure 1 for the purpose of deflecting the ascending or descending gases toward these restrictions, the movement of the gases being indicated by the arrows in Figure 1.

Gas is supplied to the heater through the gas pipe 16 which is provided with the usual control valve 17, and the burner 18 at the end of the pipe is located in the bottom portion of the up-draft passage of the return-flue.

The lower end of the heater is provided with a circular head 19, and the outlet opening 20 from the flue opens into an elbow or bent pipe 21 which is connected to the upright pipe 22 that leads to a suitable flue 23. The burner is introduced through an opening in the lower head 19, and the latter is removable to permit access to the interior 20 of the heater for removal of the inner flue 12, after the screw cap 11 has been removed. By the removal of these parts the interior walls of the flue, its partition and baffle plates, are readily accessible for cleaning or scraping 25 to remove therefrom accumulations of soot etc. deposited by the hot gases through the flue.

As thus constructed it will be apparent that an extensive heating area is provided 30 for the flue, the walls of the flue are intensely heated by the deflected gases as they pass therethrough and the thin jacket of water in the annular space surrounding the flue is quickly and thoroughly heated to insure 35 a rapid circulation and make available a large supply of hot water through the stand boiler.

Having thus fully described my invention, what I claim as new and desire to secure 40 by Letters Patent is—

1. A water heater comprising a tank having inlet and outlet connections, an interior flue forming an annular water space, a vertical partition within said flue and baffle 45 plates thereon, an exterior flange on the flue and a screw cap on the tank for said flange, a removable head at the lower end of the tank and flue having an outlet and an outlet pipe connected thereto for gases, and a burner located in an opening in said head and enclosed within the lower end of the flue.

2. A water heater comprising two tubular casings of unequal length and diameter each closed at one end, the smaller being mounted 55 concentrically within the larger and having its open end joined to the open end of the larger by an annular closure for the otherwise open end of the chamber thus formed between the two casings, a partition 60 dividing the smaller casing longitudinally into two parallel flue passages of equal length connected by an opening formed between the closed end of said casing and said 65 partition, water inlet and outlet connections

to said chamber, and a burner mounted in one of said flue passages.

3. A water heater comprising a tubular casing mounted vertically and having a closed top, another tubular casing of smaller 70 length and diameter mounted concentrically within the larger casing and having a closed top and a flange on its lower end arranged to form a closure for the lower end of said larger casing, a vertical partition in said 75 smaller casing dividing it into a return flue having connecting updraft and downdraft passages terminating at the base of the smaller casing, a burner mounted in the lower end of the updraft passage, and water 80 inlet and outlet connections in said larger casing.

In testimony whereof I affix my signature.

EDWIN L. BADGER.
